UNITED STATES PATENT OFFICE.

DUNHAM A. WEAVER, OF ELMIRA, NEW YORK.

LIQUID-FUEL DISTRIBUTING TANK.

Application filed November 11, 1922. Serial No. 600,243.

To all whom it may concern:

Be it known that I, DUNHAM A. WEAVER, a citizen of the United States, residing at Elmira, in the county of Chemung and 5 State of New York, have invented certain new and useful Improvements in Liquid-Fuel Distributing Tanks, of which the following is a specification.

This invention relates to liquid fuel tanks, 10 and has for the primary object thereof, a means for adequately discharging the fuel from the tank in a simple and convenient manner.

A further object of the invention resides 15 in the provision of a distributing tank for liquid fuels, wherein the same is simple of construction, inexpensive of manufacture, and highly useful of purpose.

The nature and advantages of the invention will be better understood when the 20 following detailed description is read in connection with the accompanying drawings, the invention residing in the construction, combination, and arrangement of parts as 25 claimed.

In the drawings forming part of this application, like numerals of reference indicate similar parts in the several views, and wherein:—

30 Figure 1 is a side elevational view of a fuel tank constructed in accordance with the present invention.

Figure 2 is a vertical cross sectional view of the tank shown in Figure 1.

35 Figure 3 is a transverse sectional view upon the line 3—3 of Figure 1, and

Figure 4 is an enlarged fragmentary view of a portion of the fuel tank, showing the improved fuel gauge associated therewith.

40 Referring to the drawing in detail, the tank comprises a vertically disposed relatively large cylinder 1, closed at its bottom end and having supporting legs 2 formed or secured thereon. The upper open end 45 of the cylinder 1 has an annular projecting flange 3 formed thereon for receiving the similar flange 4 of an annular head 5, bolts 6 engaging through these flanges. The head 5 has a central opening 7 therein and formed therearound is a screw 50 threaded nipple 8, for receiving a screw securing cap 9.

The bottom wall of the cylinder 1 has a screw threaded opening therein for the screw threaded end of a water pressure pipe 10, this pipe 10 being preferably a

water pipe from the still water main and has a globe valve 11 therein. Upon the bottom of the cylinder, there is also formed another screw threaded opening for receiving the screw threaded end of an outlet pipe 12 having a similar valve 13 therein.

Positioned for sliding movement within the cylinder 1, is a piston 14 having suitable packing rings 15 therearound and it 60 will be readily understood that in the primary use of this fuel tank, the piston is at the bottom of the cylinder, at which time, fuel is received within the cylinder above the piston 14, through the inlet opening 7 in the head 5, the cap 9 being removed. The head 5 is provided with an outlet pipe 16, having a valve 17 therein and when it is desired to remove the fuel from this cylinder, the valves 17 and 11 in 65 the outlet pipe 16 and water inlet pipe 10 are opened for allowing the water under pressure to contact with the undersurface of the piston 14, for forcing the same upwardly, and for consequently discharging 70 the fuel from the cylinder. When the cylinder has been emptied of the fuel, and it is desired to again fill the same, the valve 13 is opened, the valve 11 being closed 75 for allowing the water to drain out of the cylinder beneath the piston 1.

Referring particularly to Figure 4, the head 5 is shown as being provided with a fuel gauge 16, and this gauge constitutes a centrally bored screw threaded plug 17 90 received within a screw threaded opening 18 in the head 5, and is channeled upon its upper surface for providing a seat for the glass cylinder 18. This cylinder having a head 19 at its upper end secured to the 95 plug 17 by vertically extending rods 20 between the plug and head. Adapted for sliding movement through the central bore in the plug 17, is a rod 21 enlarged at its upper end as at 22, the lower end of this rod adapted to extend downwardly within the cylinder to be forcibly engaged by the piston 14, when the same is at substantially the limit of its upward movement within the cylinder for consequently moving the 100 enlarged end 22 of the rod upwardly within the glass cylinder 18 for indicating the position thereof to the attendant.

While it is believed that from the foregoing description, the nature and advantages of the invention will be readily apparent, I desire to have it understood that 110

I do not limit myself to what is herein shown and described, and that such changes may be resorted to when desired as fall within the scope of what is claimed.

5. What I claim as new is:—

An indicator device adapted to be used upon a fuel distributing tank having a piston movable therein comprising a plug adapted to be screwed into the tank provided with a central bore and with a recess leading in from its outer face and provided at its bottom wall with a socket, the recess and the socket being concentric with the bore, a transparent cylinder having its lower end received within the recess, a head mounted upon the upper end of the cylinder and closing the same, rods disposed exteriorly of the cylinder and connecting

the head with the plug, a rod fitting snugly within the bore of the plug and slidably mounted therein, said rod having a diametrically enlarged head adapted to fit snugly in the socket, the internal diameter of the cylinder being greater than the diameter of the head of the rod, the sum of the length of the rod and the enlarged head thereof being greater than the length of the cylinder whereby the piston in the fuel tank is adapted to contact with the end of said last mentioned rod for moving the head thereon in the cylinder to indicate the position of the piston.

In testimony whereof I affix my signature.

DUNHAM A. WEAVER.
